ILLUMINATING DEVICE

John McClain, Chicago, Ill.

Application February 6, 1936; Serial No. 62,595

2 Claims. (Cl. 240—2.18)

This invention relates generally to illuminating devices and more particularly to devices for illuminating the interior surfaces of tubes for purposes of inspection.

5 After a periodic cleaning of tubes, having particular reference to those used in stills, boilers, and the like, it is necessary to thoroughly inspect the interior surfaces thereof, so that any which are badly corroded or which have bulges 10 or hollows in their walls, may be discovered and replaced before actual failure occurs.

The present method of inspection includes placing a light, usually an ordinary pocket flashlight or the like, in one end of the tube and viewing the interior surface from the other end. 15 This method has the disadvantage that direct rays from the source of light pass directly through the tube and strike the eye of the inspector. This glare naturally impairs the efficiency of inspection as well as being injurious and annoying to the inspector. As these ill effects increase with increasing intensity of the source of light, it is necessary to use a light of 20 comparatively low intensity, consequently the surface to be inspected cannot be illuminated to the extent that is required for maximum efficiency of inspection.

The object of my invention is to provide means 30 for casting or directing light upon the interior surface of the tube, but preventing direct rays of light from the source from striking the eye of the observer, thereby permitting a higher intensity of illumination on the surface to be inspected.

Another object relates to a means for quickly aligning the source of light substantially on the axis of the tube so that the light is evenly distributed around the interior surface thereof.

40 A further object has to do with shutting out daylight and light from external sources other than that from the illuminating device, in order to further insure freedom from glare.

Still another object relates to provision for 45 adjusting the directed light, to accommodate the illumination to tubes of different lengths and diameters so that light will be supplied to substantially the entire inside surface.

I will now describe an embodiment of my 50 invention, reference being had to the drawing appended to, and made a part of this specification, in which

Figure 1 is a sectional elevation of a device embodying the principles of my invention, taken 55 along a line 1—1 in Figure 2.

Figure 2 is an end view of the illuminating device.

Figure 3 is a sectional view of a tube and the device, showing the method of operation.

Like numerals refer to like parts throughout the specification and drawing.

Referring to Figure 1, the illuminating device 1 comprises a tubular housing 2 which has one open end 3, the other end being closed by a back wall 4 on which is connected a handle 5.

Secured to the back wall 4 is a source of light comprising an electric lamp 6 held in a socket 7, which in turn, is fastened to the wall 4 by a hollow threaded post 8 and a nut 9. An electric supply cable 10 extends through the hollow post 8 into the socket 7, where suitable connection is made. The lamp is disposed substantially on the longitudinal axis of the housing 2.

The housing is provided with a distended portion 11 which presents a frusto-conical surface 12 that is substantially coaxial to the housing itself. An extended lip 13 encircles the open end 3 of the housing, the interior surface 14 of the lip 13 being tapered inwardly.

A frusto-conical member 15, made of any opaque material, is disposed in the open end 3 substantially on the longitudinal axis of the housing and in alignment with the light source. It has a reduced threaded supporting portion 16 which screws into a tapped lug 17. This lug is supported from the housing on a pair of arms of brackets 18, which can be seen in Figure 2. Hence by rotating the member 15 around its longitudinal axis, its position can be adjusted along the axis, and can be set closer to, or farther from, the lamp 6 as desired.

The end of a tube 19 is indicated in Figure 2. To place the device 1 in operating position, the housing is placed with its open end 3 in register with the end of the tube, and then inserted until the frusto-conical surface 12 engages the tube 19. By holding the housing parallel to the tube, it can then easily be guided into the position shown, by means of the guiding surface 12. In the operating position the axis of the housing falls substantially on the axis of the tube, and daylight and other light from exterior sources are shut out of the tube by the surface 12 of the distended portion 11, engaging the end of the tube 19, its tapering surface enables the device to fit equally well in tubes of different diameters.

The light from the lamp 6 is now directed into the tube in a conical beam indicated by the reference letter A. This beam or cone of light is, however, hollow, that is to say, the direct

rays from the light source are intercepted and diverted by means of the intercepting member 15 from the central space B of the conical beam A.

Figure 3 illustrates this effect as produced throughout the length of the tube 3. The space B, within the beam, which receives no direct rays of light from the source, thus gradually widens toward the other end 20 of the tube 19, so that from the point of view of an observer (shown by the arrow) no direct glare from the lamp is received, substantially all the light reaching the point of view being that reflected from the interior surface 21 of the tube 19.

I recognize, of course, that there will in fact, be no clearly defined shadow in the central space B as shown, as this space will be illuminated by reflected light. The illustration is made in this way in order to show the space from which direct light rays are excluded.

By screwing the intercepting member 15 toward or away from the light source, the cross-sectional area of this shaded portion B at the end 20 of the tube, can be enlarged or contracted, and the distance that light from the lamp 6 is projected along the interior of a given tube can thus be adjusted.

Furthermore adjustments can be made for different lengths and sizes of tubes. For example, if the device were to be used without adjustment to illuminate another tube of greater length or smaller diameter than the one shown in Figure 3, the beam of direct light rays would not reach the surface of the tube near the far end 20, hence an adjustment of the intercepting member 15 away from the source of light would be required. Conversely if a shorter or larger diameter tube were inspected, an adjustment of the member toward the lamp would be desirable to prevent direct light rays from the source from passing directly through the tube and out of the other end.

Having thus eliminated direct, glaring rays from the lamp from the point of view, it is possible to use a lamp of appreciably higher intensity than those employed heretofore, thereby raising the intensity of illumination at the interior surface 21 of the tube to any extent that

is found to be desirable and conducive to more efficient inspection.

I do not intend to limit my invention to the details shown and described herewith, but what I desire to protect by Letters Patent of the United States is set forth in the following claims.

I claim:

1. A device for illuminating the interior surfaces of tubes for inspection purposes, said device comprising a portable tubular housing having an open end adapted for insertion into one end of a tube, a source of light within said housing, a distended portion on said housing for engaging the end of said tube for shutting out other light than light from said source and for guiding said housing so that said source of light can be easily centered on the longitudinal axis of said tube, an opaque member supported by said housing in substantial alignment with said source of light on the axis of the tube in a position between said source and the far end of the tube, for preventing direct rays of light from said source from passing directly out through said far end of the tube, and means for adjusting the position of said member with respect to said light source. 20 25

2. A device for illuminating the interior surfaces of tubes for inspection purposes, said device comprising a portable tubular housing having an open end adapted for insertion into one end of a tube, a source of light within said housing, a portion of said housing being adapted to engage the end of said tube for shutting out other light than light from said source and for guiding said housing to facilitate centering the source of light on the axis of said tube, a frusto-conical light intercepting member disposed adjacent the open end of said housing and in a position with the axis of said frusto-conical member substantially coaxial with the longitudinal axis of the housing and with the smaller end of the member toward the source of light, and a support for said member fixed on said housing and having a threaded portion adapted to cooperate with said member for adjustably setting the position of the latter. 30 35 40 45
